UNITED STATES PATENT OFFICE

FRITZ WINKLER AND HANS HAEUBER, OF LUDWIGSHAFEN-ON-THE-RHINE, GERMANY,
ASSIGNORS TO I. G. FARBENINDUSTRIE AKTIENGESELLSCHAFT, OF FRANKFORT-
ON-THE-MAIN, GERMANY, A CORPORATION OF GERMANY

PRODUCTION OF VALUABLE HYDROCARBONS

No Drawing. Application filed December 27, 1928, Serial No. 328,849, and in Germany January 5, 1928.

This invention relates to improvements in the manufacture and production of valuable hydrocarbons, especially those of liquid nature, although the production of gaseous hydrocarbons, for example diolefines, such as butadiene or its homologues is also contemplated.

It is already known that hydrocarbons of higher molecular weight than that of the initial material can be produced by heating mixtures comprising olefines and acetylene; for example, it is known that, inter alia, butadiene can be obtained by heating a mixture of ethylene and acetylene in a glass retort to such a temperature that the said retort is brought to redness. But glass, quartz, porcelain, iron, nickel, copper, silver and many other materials suitable for the apparatus used in this reaction, cause extensive deposition of carbon and for this reason it has not hitherto been possible to carry out the process on a technical scale, because this is only practicable when the deposition of carbon is prevented.

We have now found that the said conversion of olefines, such as ethylene or propylene together with acetylene can be carried out at high temperatures and without deposition of carbon if care be taken that the heated gases and vapors come into contact only with free elements of group 4 of the periodic system, such, for example, as tin, silicon, lead, carbon in the form of graphite, or with zinc or aluminium or alloys containing substantial amounts of these metals. With this object in view it is essential that such hot portions of the conversion apparatus as come into contact with the gases and vapors should be constructed of the said metals or alloys or should be coated with them. The operation can also be conducted by simply passing the mixtures of olefines and acetylene under treatment through a highly heated bath of molten tin, zinc, lead, aluminium, or alloys of these metals with one another or with other metals which do not cause deposition of carbon, or with silicon or graphitic carbon.

The process may be carried on under elevated, atmospheric or diminished pressure. Usually pressures of up to about 50 or 100

atmospheres are employed, but, if desired, higher pressures, for example 200 atmospheres or more, may also be employed. The reaction is usually carried out between about 200° and 800° C. and preferably between about 300° and 600° C.

The materials hereinbefore specified not only prevent the deposition of carbon, but also to a large extent exert a catalytic action. It is therefore advantageous to dispose them, for example, on plates, in the reaction chamber.

It has also been found that the operation may be carried on in the presence of catalytic substances having a condensing action other than those hereinbefore specified. Anhydrous chlorides of the heavy metals, such as ferric chloride, zinc chloride and the like and also aluminium chloride having proved especially efficacious.

The gaseous mixture entering into the reaction may consist of equal parts by volume of the olefine and acetylene or the olefine may be in excess, and, if desired, the mixture may be diluted with one or more extraneous gases, for example nitrogen, methane or ethane, carbon dioxide or carbon monoxide.

The latter method of operating may also be carried on under elevated or diminished pressure.

The following examples will further illustrate the nature of the said invention, but the invention is not restricted to these examples. The parts are by weight.

Example 1

A mixture of equal parts of ethylene and acetylene is passed, from above downwards, at about from 525° to 550° C., through a vertical, externally heated aluminium tube, in which metallic silicon is disposed on a plate. About 39 per cent of the gaseous mixture is converted into valuable products of which 10 per cent, consisting mainly of butylene, boils below ordinary temperature, 70 per cent, consisting mainly of benzene and toluene, boils up to 120° C., and the rest boils up to 200° C. There is no formation of tar and no appreciable deposition of carbon.

Example 2

An iron high pressure vessel, the interior surface of which is coated with tin and then with powdered silicon, and in which silicon 5 is disposed on plates, is charged with a mixture of 20 per cent of acetylene, 60 per cent of ethylene and 20 per cent of nitrogen, so that an initial pressure of 50 atmospheres is produced. On being heated to about from 10 370° to 400° C., the reaction commences whereupon the same temperature is maintained for about 6 hours. On cooling, 72 per cent by weight of the mixture of ethylene and 15 acetylene employed is recovered in the form of oil, of which 10 per cent, consisting mainly of butylene, boils below ordinary temperature, 70 per cent, consisting mainly of benzene and toluene, boils up to 120° C., and the rest boils up to 150° C. The catalyst remains 20 perfectly free from tar or carbon.

Example 3

A mixture of 9 parts of ethylene and 1 part of acetylene is passed, at the rate of 10 25 liters per hour, through a manganese-copper tube coated internally with tin, 18 millimeters in diameter, which is heated over a length of 60 centimeters to about 600° C. 30 4 per cent of the transmitted gases is continuously converted, and the tube does not show the slightest deposition of carbon, even after prolonged use.

The condensate obtained on cooling to low 35 temperatures contains 13 per cent of butadiene, which can be readily identified in the form of tetrabromide by adding on bromine. A further 7 per cent of the converted materials boils below ordinary temperatures and the remainder boils up to about 95° C. The 40 residual gas contains ethylene, acetylene, a little propylene and butylene, and also 0.5 per cent of methane. It can be employed for the process again after the addition of acetylene, which is the chief constituent consumed. 45

Example 4

The same conversion as described in Example 3 is carried on in a manganese copper 50 tube coated internally with zinc. 5.5 per cent of the gas is converted into a liquid which boils, for the most part at between about 60° C. and 80° C., and consists almost entirely of benzene. Merely traces of butadiene can be detected in the conversion mixture, and only traces of methane are present in the residual gas. No deposit of carbon can be found in the tube itself after being in use for 120 hours. Benzene is also obtained as 60 the chief product by operating, in a similar way, at about 600° C., with a brass tube.

The tube may be replaced, for example, by an electrically heated tinned radiator of manganese copper wire. The operation may 65 also be conducted under elevated pressure.

Tin, zinc and the like have also proved very advantageous for internally coating the apparatus, in cases, where gases obtained by the pyrogenic decomposition of tars, oils, bituminous coals and the like and which contain olefines and acetylene, for example, 20 to 40 per cent of the former and about 1 to 2 per cent of the latter, are subjected to the aforesaid treatment, since the said metals prevent the deposition of carbon. 75

What we claim is:—

1. In the production of valuable hydrocarbons by heating a mixture comprising an olefine and acetylene, the step of bringing the said initial materials, while in the hot state, only into contact with substances selected from the class consisting of carbon, silicon, lead, tin, zinc, aluminium and alloys containing substantial amounts of these metals. 80

2. In the production of valuable hydrocarbons by heating a mixture comprising an olefine and acetylene, the step of bringing the said initial materials, while in the hot state, only into contact with substances selected from the class consisting of carbon, silicon, lead, tin, zinc, aluminium and alloys containing substantial amounts of these metals, and maintaining a temperature of between about 200° and 800° C. 85

3. In the production of valuable hydrocarbons by heating a mixture comprising an olefine and acetylene, the step of bringing the said initial materials, while in the hot state, only into contact with substances selected from the class consisting of carbon, silicon, lead, tin, zinc, aluminium and alloys containing substantial amounts of these metals, and maintaining a temperature of between about 300° and 600° C. 90

4. In the production of valuable hydrocarbons by heating a mixture comprising an olefine and acetylene, the step of bringing the said initial materials, while in the hot state, only into contact with substances selected from the class consisting of carbon, silicon, lead, tin, zinc, aluminium and alloys containing substantial amounts of these metals, and maintaining an elevated pressure. 105

5. In the production of valuable hydrocarbons by heating a mixture comprising an olefine and acetylene, the step of bringing the said initial materials, while in the hot state, only into contact with substances selected from the class consisting of carbon, silicon, lead, tin, zinc, aluminium and alloys containing substantial amounts of these metals, and employing the initial mixture in dilution with an extraneous gas. 115

6. In the production of valuable hydrocarbons by heating a mixture comprising an olefine and acetylene, the step of bringing the said initial materials, while in the hot state, only into contact with substances selected from the class consisting of carbon, silicon, lead, tin, zinc, aluminium and alloys containing substantial amounts of these metals, and 120

ing substantial amounts of these metals, and treating the said mixture with a catalyst comprising an anhydrous metal chloride.

7. In the production of valuable hydrocarbons by heating a mixture comprising an olefine and acetylene, the step of bringing the said initial materials, while in the hot state, only into contact with substances selected from the class consisting of carbon, silicon, lead, tin, zinc, aluminum and alloys containing substantial amounts of these metals, and treating the said mixture with a catalyst comprising aluminum chloride.

8. In the production of valuable hydrocarbons by heating a mixture comprising an olefine and acetylene, the step of bringing a mixture comprising ethylene and acetylene, while in the hot state, only into contact with substances selected from the class consisting of carbon, silicon, lead, tin, zinc, aluminium and alloys containing substantial amounts of these metals.

9. In the production of valuable hydrocarbons by heating a mixture comprising an olefine and acetylene, the step of bringing a mixture comprising ethylene and acetylene, while in the hot state, only into contact with substances selected from the class consisting of carbon, silicon, lead, tin, zinc, aluminium and alloys containing substantial amounts of these metals, and maintaining a temperature of between about 300° and 600° C.

10. A process for the production of valuable hydrocarbons, which comprises passing a mixture comprising ethylene and acetylene through a tube coated internally with tin and heated to about 600° C.

In testimony whereof we have hereunto set our hands.

FRITZ WINKLER.
HANS HAEUBER.
